ADJUSTABLE CLAMP TRUCK

Henry L. Smith, Clearwater, Fla., assignor to
Food Machinery and Chemical Corporation, a
corporation of Delaware

Application October 1, 1947, Serial No. 777,314

4 Claims. (Cl. 214—65.5)

1

This invention relates to the art of clamp trucks and particularly to such trucks which are adjustable to loads varying in width.

It is an object of this invention to provide a novel adjustable clamp truck, having an over-riding toggle locking the truck in clamping position, with a novel means for adjusting the truck to handling boxes varying in length so that when thus locked it will fit a box of a particular length in accordance with the adjustment of the truck.

Another object of the invention is to provide a toggle locking clamp truck with a mechanism for adjusting the space between the jaws, when these are in clamping relation, which is relatively simple to operate and which is universal in the degree of adjustment, that is: which can be set anywhere between the maximum and minimum limits of the adjustment.

The manner of accomplishing the foregoing objects as well as further objects and advantages will be made manifest in the following description taken in connection with the accompanying drawings in which:

Fig. 1 is a front elevational view of a preferred embodiment of the hand truck of this invention with the truck adjusted for a minimum separation of the jaws and showing the latter in clamping position.

Fig. 2 is a side elevational view of Fig. 1.

Fig. 3 is an enlarged vertical sectional view taken on the line 3—3 of Fig. 1 and illustrating the adjusting screw and guide shaft of the clamping mechanism.

Fig. 4 is a fragmentary front elevational view similar to the lower portion of Fig. 1 and showing the same adjustment of the truck with the clamping mechanism actuated to extend the jaws preliminary to a clamping operation.

Fig. 5 is a view similar to the lower portion of Fig. 1 with the mechanism adjusted to the maximum spacing of the jaws in clamping position.

Fig. 6 is a view similar to Fig. 5 showing the jaws expanded in readiness to receive a load between the jaws.

Fig. 7 is an enlarged horizontal cross-sectional view taken on the line 7—7 of Fig. 5.

Fig. 8 is a similar view taken on the line 8—8 of Fig. 5.

Referring specifically to the drawings, the clamp truck 10, shown therein as embodying the invention, includes a carriage frame 11 having handle side members 12 which are rigidly connected and held in spaced relation by an upper cross-member 13, a middle cross-member 14 and lower cross-members 15 and 16, the latter extend-

2

ing outwardly from the members 12 and having guide lugs 17 thereon.

The members 13, 14, 15 and 16 are recessed into the front faces of the side members 12 and are held in place by metal straps 18 which are bolted to the front faces of the side members.

Bearing plates 19 are also recessed into the lower ends of the side members 12 and secured thereto by the same bolts which attach the straps 18 to these members.

Provided on the members 12 are blocks 25 in which is fixed a shaft 23, carriage wheels 27 being mounted on this shaft just inside the blocks 25.

Shaft 26 also carries a pedal bracket 28 on which is pivotally mounted a clamping pedal 29.

Provided on the cross-members 13 and 14 are bearings 35 and 36 in which is journaled a shaft 37 having a smooth portion 38 and a threaded portion 39. Collars 40 prevent vertical shifting of the shaft 37 in the bearings 35 and 36. The shaft 37 is adapted to be rotated by a handle 41 mounted on its upper end.

Laterally shiftable through the openings 25 formed between the members 15 and 16, bearing plates 19, and straps 18, are box clamping jaws 42, these having arms 43 bent forwardly therefrom, with box gripping teeth 44 extending inwardly from outer lower edges of these arms. These jaws 42 lie flush with the cross-members 15 and 16.

Disposed parallel with the shaft 37, and on opposite sides thereof, are pairs of guide bars 45 which are secured to the front and rear faces 35 of the cross members 14 and 15 so that the bars of each pair are parallel.

Pivoted at their lower ends on the jaws 42 are levers 46, each of these comprising a bar which lies flush against the cross-member 15 and one of the jaws 42.

Slideable on the smooth shaft portion 38 is a slide block 50 while the threaded portion 39 is screwed into a screw block 51. The block 50 has vertical kerfs in which are pivoted links 53, the outer ends of which are pivotally connected to the upper ends of the levers 46. The block 51 has vertical kerfs in which are pivoted links 55, the outer ends of which are pivoted at fulcrum points 56 to the levers 46. The slide block 50 has a jaw opening pedal 60 which is connected by a link 61 to the upper end of the clamping pedal 29.

Operation

In Fig. 1, the slide block 50 is in its uppermost position to which it was elevated by the opera-

tor depressing the foot pedal 29. This separates the upper ends of the levers 46 and shifts the jaws 42 inwardly into their innermost box clamping position.

The block 51 is adjusted as shown in Fig. 1 when it is desired to handle a stack of boxes, the length of which equal the distance here shown between the inner faces of the arms 43 of the jaws 42. No boxes are shown in Fig. 1 as they would hide the mechanism. If the truck 10 were so adjusted and then operated on such a stack, the teeth 44 would be driven along the top surface of the floor beneath the ends of the lowermost box of the stack. The operator would then continue to press his foot on the pedal 29, while pulling backward vigorously on the upper ends of the handle members 12 so as to lift the stack and balance this on the wheels 27 while trucking it to a desired destination.

The stack is set down by reversing the steps of the process by which it was picked up. The operator then trocks on the pedal 60 which depresses the slide block 50 and swings the upper ends of the levers 46 inwardly into the position in which these are shown in Fig. 4.

This expands the jaws 42, releasing the stack and permitting the truck to be withdrawn from about the stack.

When the jaws have been shifted inwardly (as shown in Fig. 10) to grip and support a stack of boxes so that this may be carried from place to place on the truck 10, it is to be noted that the slide block 50 has been lifted so as to overthrow the toggle (comprised by the links 53) past the line connecting the pivots at which these links are joined to the upper ends of the levers 56. This prevents accidental expansion of the jaws 42 while a load is being carried on the truck 10.

The adjustment of the truck 10 for handling boxes of any particular length, between the minimum and maximum lengths indicated in Figs. 1 and 5, is accomplished by rotating the shaft 31 by the handle 41. The action of the threads on the threaded portion 39 of the shaft 31 moves the block 50 up or down which varies the spacing between the fulcrum points 56 of the levers 46. As this distance increases the distance between the jaw arms 43 increases both for their expanded and clamping positions.

A particular advantage of the truck 10 is that merely by rotation of the handle 41, the truck may be adjusted to fit any particular length of box in between the maximum and the minimum sizes the truck is adapted for handling.

It is also helpful that this adjustment may be made while the truck is resting close to a stack just before the operator undertakes to pick the stack up with the truck. As he rotates the handle 41 he may look downwardly at the stack and compare its width with the space between the arms 43 while the pedal 29 is depressed. When this spacing of the arms 43 is exactly equal to the length of the boxes of the stack, the operator then merely depresses the pedal 60 and proceeds to pick up the stack in the manner above described.

I claim:

1. In a clamp truck the combination of: a wheeled carriage frame; a pair of box clamping

jaws mounted on said frame for movement inwardly from expanded position to clamping position and return; a pair of upright levers the lower ends of which connect with said jaws; a vertical shaft lying substantially in the plane of said levers and between these; means for rotatably mounting said shaft on said frame; threads on a portion of said shaft, said shaft also having a smooth portion; a slide block slideable on said smooth portion of said shaft; links pivotally connected to said slide block and to upper ends of said levers; a screw block into which the threads of said shaft are screwed; links pivotally connecting at their inner ends with said screw block at their outer ends with said levers at fulcrum points on the latter; means for shifting said slide block on said shaft to rock said levers about said fulcrum points to expand or retract said jaws on said truck; and means to rotate said shaft to alter the spacing of said fulcrum points.

2. A combination as in claim 1 in which vertical guide bars are provided in pairs for guiding said links and blocks in their various movements.

3. A combination as in claim 2 in which said slide block and screw block have kerfs into which said links extend and in which said links are pivoted to said blocks; said pairs of guide bars being spaced apart substantially the width of said slide blocks, the bars in each pair being spaced substantially the thickness of said links.

4. In a clamp truck the combination of: a frame comprising a pair of handle side members; a pair of wheels rotatably journaled on said side members; at least three cross-members rigidly uniting said frame side members; a pair of box clamping jaws slideably mounted on the lower of said cross-members; bearing means provided on two of said cross-members; a shaft journaled in said bearing means, said shaft having a threaded portion and a smooth portion; a screw block into which said threaded portion screws; a slide block slideably receiving said smooth portion of said shaft; two levers, the lower ends of which are pivotally connected respectively to said jaws; links connecting said screw block to said levers at fulcrum points thereon; links connecting said slide block to other points on said levers; means for vertically moving said slide block on said shaft to shift said jaws inwardly and outwardly between expanded and box clamping positions; guides for guiding said clamping jaws along rectilinear paths; and means for rotating said shaft to move said screw block to various adjusted positions on the shaft to alter the distance said fulcrum points are separated.

HENRY L. SMITH.
